DISPLAY BOX FOR AN ELECTRIC RAZOR OR THE LIKE

Samuel Braun, Rye, N.Y., assignor to B.C.N. Design
Products Inc., Long Island, N.Y., a corporation of New
York

Filed May 29, 1962, Ser. No. 70,341

Term of patent 14 years

(Cl. D58—12.6)

FIG. 1

FIG. 2

FIG. 3

FIG. 4

FIG. 5

FIG. 7

FIG. 6

FIG. 1 is a top plan view of a display box for an electric razor or the like, showing my new design.

FIG. 2 is a bottom plan view thereof.

FIG. 3 is a side elevational view thereof.

FIG. 4 is a front elevational view thereof.

FIG. 5 is a rear elevational view thereof.

FIG. 6 is a side elevational view thereof in opened position.

FIG. 7 is a top perspective view thereof in opened position.

I claim:

The ornamental design for a display box for an electric razor or the like, as shown.
